DISPLAY DEVICE

Robert L. Joyce, Columbus, Ohio

Application July 7, 1937, Serial No. 152,396

2 Claims. (Cl. 211—143)

My invention relates to display devices, and more particularly to devices for displaying articles, such as samples of fabric and the like.

One of the objects of my present invention is to provide a display device in which the hinged shelves, used for carrying the displays of merchandise, are adapted to be arranged parallel with one another and are each movable by longitudinal displacement.

10 In carrying out the above object it is a further object of my invention to provide each shelf with guiding means which means are associated with the shelf on opposite ends of one edge thereof, the guiding means being movable along tracks, 15 for guiding the shelf during the longitudinal displacement thereof and being pivoted, with respect to the track for allowing partial rotational movement of the shelf around the guiding means when such movement is desired.

20 It is a further object to provide guiding means for each shelf, which means are disposed at opposite ends of the one edge of the shelf, such guiding means being associated with one another so that they are substantially unitary and so that they rotate, or pivot, concomitantly during 25 longitudinal displacement of the shelf.

It is a further object to provide spacing means for spacing the shelves one from another when they are in the stacked position, the spacing means in some cases being integral with the 30 aforementioned guiding means.

It is a further object to provide each shelf with means for attaching the displays thereto, said means permitting ready removal of, or addition to, the displays on the shelf.

35 It is a further object to provide each shelf with a cross bar which is disposed so as to be slidable across the shelf for further retaining the displays in position.

40 It is a still further object to provide a label holder for each shelf, which holder is movably carried by the cross bar.

Other and further objects and advantages will be apparent from the following description, reference being had to the accompanying drawings wherein preferred forms of embodiments of the 45 present invention are clearly shown.

In the drawings:

Fig. 1 is a front view of the display device with 50 the shelves in the stacked position;

Fig. 2 is a side view of the device;

Fig. 3 is a top plan view of the device, the present view being taken in the direction indicated by the arrow in Fig. 2;

55 Fig. 4 is a view similar to Fig. 3 but showing one of the shelves in the open position;

Fig. 5 is a front view of the device showing a shelf in the open position, a second shelf in a 60 partial open position, a third shelf, shown in

dotted lines, in a revolved position and a fourth shelf on the base of the device;

Fig. 6 is a fragmentary view, partially in section, of one end of a track showing the means utilized for securing the same to the base; 5

Fig. 7 is a top view of one of the guide means;

Fig. 8 is a side view of Fig. 7 showing the offset spacing means provided on the guide ring bracket;

Fig. 9 is a view of a shelf handle and support 10 spacer, taken on line 9—9 of Fig. 4, the view also showing the adjustable rod for preventing displacement of the displays;

Fig. 10 is a fragmentary side view of the label 15 holder;

Fig. 11 is a fragmentary sectional view taken on line 11—11 of Fig. 6 showing a reinforcing plate;

Fig. 12 is a fragmentary sectional view taken on line 12—12 of Fig. 9 showing the adjustable 20 rod and one support bracket therefor;

Fig. 13 is a fragmentary sectional view taken on line 13—13 of Fig. 4 showing the spring fastening means for the displays;

Fig. 14 is a plan view of a display device employing another form of guiding means; 25

Fig. 15 is a fragmentary view of the reverse side of the shelf shown in Fig. 14 with part of the shelf cut away to show the guide bushings and guide rod; 30

Fig. 16 is a fragmentary view on an enlarged scale of one end of the guide rod utilized in Fig. 15 showing one of the guide bushings therefor;

Fig. 17 is a section of the rolled edge of the shelf taken on line 17—17 of Fig. 16; 35

Fig. 18 is a fragmentary sectional view of another type of track showing one end of the guiding means;

Fig. 19 is a fragmentary sectional view taken on line 19—19 of Fig. 18; 40

Fig. 20 is a sectional view taken on line 20—20 of Fig. 18;

Fig. 21 is a fragmentary side view of still another form of track and guiding means, showing the mounting bracket for attaching the track to 45 the base; and

Fig. 22 is a sectional view taken on line 22—22 of Fig. 21.

In the embodiment illustrated in Figs. 1 to 12, a sheet metal base 20 is utilized to support and 50 carry the various parts of a display device 21. The base 20 comprises four vertical side walls 22 and a top section 24. The base 20 is fabricated, in its preferred form, so that the top 24 is at an angle to the horizontal, to permit more ready 55 examination of the merchandise to be displayed. The side walls 22 are bent inwardly at the lower edges thereof to form flanges 26. Suitable downwardly extending projections 27 are formed in the flanges 26 to act as gliders for the device 60

21 so that the device 21 may be easily slid along a counter or a floor.

Two tracks 28 and 30, of substantially inverted U shape metal tubing, are mounted on the top 24 and extend substantially the length of the base at the front and back sides thereof and comprise two upwardly extending portions 29 and a connecting member 31. The tracks 28 and 30 are secured to the top 24 of base 20 by screws 32, which screws pass through holes 34 in the top 24 and are threaded into bushings 36. These bushings are pressed into the open ends of the tubular tracks 28 and 30. The bushings 36 may be slightly tapered, and knurled as at 37 to hold the bushings within the tubes and to prevent them from turning. If desired the bushings 36 may be staked within the tubes after they have been pressed into position. Thus the screws 32 attach the tracks 28 and 30 rigidly to the base 20 to form a substantially unitary frame structure therewith. In some cases, triangular shaped reenforcing members or plates 40, as shown in Fig. 11, are spot-welded to the underside of the top 24, at the four corners thereof. These plates reenforce the top 24 at the ends of the tracks when the device is to be used for heavy displays, or when a light gage metal is used in the fabrication of the base 20. In this case the holes 34 extend through the reenforcing members 40 as well as through the top 24. If desired, further reenforcements may be provided for the base 20 such as channels formed in the top 24 or in some similar and well known manner.

35 The tracks 28 and 30 are utilized to guide a plurality of display carrying shelves 42. The shelves 42 are associated with the tracks 28 and 30 by ring-like guide members 44. The rings 44 are passed over the tracks 28 and 30 before the tracks are secured to the base and are freely slideable thereon. Two such rings 44 are provided for each of the shelves 42. The guide rings 44 are each pivotally journaled on a bracket 46 by a screw 48. Brackets 46 are suitably attached 40 to the extremities of one edge of each of the shelves. The brackets 46 are offset as at 52 so that the bearings for the rings 44 are lower than the associated shelves 42. This construction is utilized as a means for spacing one shelf 45 from another at one side thereof.

55 Handles 54, preferably formed of sheet metal, are suitably attached to the shelves 42 at the side opposite to the edge which carries the guide rings 44. The handles 54 facilitate movement 60 of the shelves when the device is being used. Each of the handles 54 also include a U shaped spacing element 56. The depth to which each spacer 56 extends is substantially equal to the depth to the offset 52 of a bracket 46. Thus 65 the shelves 42 are parallelly spaced from one another by the offsets 52 of brackets 46 and by spacers 56 of the handles 54.

65 Each of the shelves 42 is provided with a clip arrangement 60 disposed along one side thereof. The clip 60 is hinged on a rod 61 which is pivoted to the shelf 42 by rolled over portions of the shelf 42 (not shown). One or more coiled springs 62 are utilized to maintain the clip 60 in the position shown in Fig. 13. The spring or springs 70 62 are suitably wound around the rod 61 and have one tail 63 bearing on the clip 60 and the other tail 63 bearing on the underside of the shelf 42. Samples, for example fabrics, may be held in place on the shelf by the use of this

spring clip arrangement, and when desired, may be easily removed.

75 Adjustable rods 68 are also provided for the shelves 42 and are utilized to further hold the fabrics in place. The rods 68 are preferably disposed as in Fig. 3. The rods 68 are bent on either end thereof to form a bell crank portion 64 which is journaled in an upright support 65 that is carried by the shelf on either side thereof. The supports 65 are provided with a plurality of 10 inwardly formed protrusions 66 disposed in a circular arc with the bearing for the rod 68 as a center. Thus the bell crank portion of the rod 68 is held between two of the protrusions 66 at either end thereof and in this manner may 15 be yieldingly held, due to the inherent spring of the rod, in any one of a plurality of adjustable positions to accommodate varying thicknesses of displays on the shelf 42 or to allow removal of the displays.

20 Label holders 74 are rotatably associated with the cross bars 68. This is accomplished by merely rolling one side of the holders 74 around the bars 68 as at 76 in Fig. 10. The label holders may be made in any suitable form. In the present embodiment of label holder, three edges 25 thereof are first turned upwardly and then inwardly to form a shallow channel as at 78 around three sides of the holder. Thus a card may be readily slipped into the channel 78 of the holder 74. The back of the holder is open also so that both sides of the card are visible. The front of the card can be printed to carry information for the customer while the back can bear notations such as the quantity of stock on hand.

35 A cover 80 is provided for the device and is associated with the tracks in the same manner as are the shelves 42. The cover 80 is similar in most respects to one of the shelves 42 except for a downwardly extending leg or side portion 82. 40 The leg 82 is cut at an angle at the edge thereof as at 84, so that when the cover is in the open position (see Fig. 5) with edge 81 resting on a flat surface, the top of the cover 80 is at substantially the same slope as at the top 24 of the 45 base 20.

50 In use of the device 21, all the shelves 42 are disposed one above the other and between the tracks 28 and 30 with the bottom shelf resting on the base 20. When it is desirable to display the material carried by the device, the cover 80 is placed in position to the right of the base 20 as shown in Fig. 5. The shelves 42 may then be displayed in succession by displacing the shelves vertically until the guide rings 44 are 55 past the upwardly extending portions 29 of the tracks 28 and 30, then pulling the shelves longitudinally to the right until the guide rings have passed the highest point of the connecting members 31 of the tracks, at which instant the shelves will move easily to the open position due to gravity. All of the shelves 42 may be displayed successively in this manner. It will be noted that the shelves 42 are not turned but are 60 displaced longitudinally with the display surface always visible and always substantially parallel to the top 24. If it is desired to compare a sample that is on a shelf in the open position with a sample that is covered by other of the shelves in the closed position, it is merely necessary to turn or rotate the shelves that are covering the desired sample. This is accomplished by revolving the shelves about their guide rings to assume the dotted line position shown in Fig. 5. Thus any two samples in the display 70 75

device can be compared simultaneously without removing them from the device.

Another embodiment of construction is shown in Figs. 14 to 17, wherein a single rod 83 is utilized as a guide means and which includes an "eye" portion 84 on either end thereof. The eye portion 84 is disposed to be slidable over the tracks 28 and 30. The rod 83 is journaled in a plurality of bushings 85 and 86 which are held by the rolled edge of the shelf 42 as shown in Fig. 17, the bushings preferably being spot welded in place. The bushings 86, which are disposed at either end of the shelf, have a shoulder portion 86', at the outer end thereof, that abuts the eye 84. This shoulder 86' provides a smooth bearing surface and eliminates any possibility of the eye catching on the shelf. The rod 83 is freely rotatable within the bushings 85 and 86 which permit ready displacement of the shelf. This embodiment has the advantage of concomitant rotational movement of the guide members, since both eyes 84 are formed on one rod. For this reason the present construction eliminates "weaving" of the guide rings and shelf when the shelf is being displaced which possibility is present when small diameter tracks are utilized.

It is apparent that if desired, the bushings 85 and 86 may be spot welded to U shaped shell metal straps, which in turn may be welded to the shelf; in this manner the rolled edge of the shelf can be eliminated when desired.

In the present embodiment, the spacing of the shelves 42 is accomplished by the supports 65 for the adjustable rod 68 and the longitudinal clip 60. Obviously any other suitable spacing means may be utilized.

Another embodiment of track construction is shown in Figs. 18 to 20 wherein tracks 87 are utilized and are of substantially C shape in cross section and having openings or grooves 91 therein. The shelves 42 are provided with rods 90 attached along one side thereof, which rods have been undercut near their extremities as at 92. The ends of the rods beyond the undercuts 92 provide ball portions 94. In the assembled form, the undercuts 92 slide within grooves 91 in the tracks and the balls 94 slide within the hollow tracks and prevent the rods from being displaced from the tracks 87, since the balls 94 are of larger diameter than the grooves 91 in the C shaped tracks. The tracks 87 may be threaded at the ends thereof, as at 96, and may be secured to the top 24 by two nuts 98 disposed on either side of the top 24. Thus the shelves are displaceable along the tracks due to the slidable engagement of the rods 90 with the tracks.

Another embodiment of track construction is shown in Figs. 21 and 22 wherein the tracks 100 are rolled or cast and each forms an inner track 102. Rollers 104, one of which is shown, are each provided with a circumferential groove 106, which groove is of inverted configuration to the inner track and which engages the inner track 102 to guide the movement of the rollers 104 along the tracks. The rollers 104 are rotatably carried on the opposite extremities of rods 101 which rods are secured to one side of each of the shelves 42, as has been explained. The tracks 100 are secured to the top 24 by brackets 108 which are screwed to the top by screws 110.

In all of the embodiments, the shelves 42 bearing the displays can be examined in successive

order without the necessity of turning the shelves and in this manner, the display being displaced is visible throughout the entire displacing operation. This is advantageous in that it is time saving for the clerk and the customer. Also, in view of the fact that one or any number of shelves can be swung to the left, as shown in dotted lines in Fig. 5, any two pieces of the material in the displace device can be placed side by side for comparison for deciding on color scheme.

Another advantage of my present invention is that a plurality of samples may be carried by each shelf and due to the fact that the shelf can be maintained in a substantially horizontal position throughout its displacement, the samples will not be overturned. Thus for example all samples of the same pattern but of different colors or similar patterns may be attached to a single shelf and all displaced simultaneously while insuring quick handling without the disturbance of upsetting the samples. Preferably the upper samples are cut away as at 112 in such manner so that the next lower sample is also visible which in turn is cut away as at 113 so that the next lower sample is also visible etc.

The bar 68 holds all of the samples on a shelf in position when the shelf is swung to the left as shown in dotted lines in Fig. 5. Also it can be movably adjusted so that the upper samples can be thrown back to more clearly show the samples therebelow.

While the forms of embodiments of the present invention as herein disclosed constitute preferred forms, it is to be understood that other forms might be adopted, all coming within the scope of the claims which follow.

I claim:

1. A display device for a plurality of movable display shelves adapted to be stacked in one position and removed and stacked in an adjacent position for displaying, comprising in combination, means forming a base; a plurality of shelves adapted to be stacked on said base; means forming a guide track, said track comprising two sections rising with respect to the base, said sections being spaced from one another at least the width of the shelves, and a track section interconnecting the rising sections; and means pivotally connecting one end of each of said shelves to the guide track whereby the opposite end of said shelves are freely movable, said connecting means being movable along the guide track.

2. A display device for a plurality of movable display shelves adapted to be stacked in one position and removed and stacked in an adjacent position for displaying, comprising in combination, a base member having means forming a pair of guide tracks on opposite sides of the base, said tracks each comprising two sections rising with respect to the base, said sections being spaced from one another at least the width of the shelves, and a section interconnecting the rising sections; a plurality of stacked shelves disposed on said base and between the rising sections of the guide tracks; and means adjacent one end of each of said shelves and on opposite edges thereof for pivotally connecting the shelves to the guide tracks, said means being movable along the guide tracks.
